UNITED STATES PATENT OFFICE.

GEORGES A. DE GUIRE, OF MONTREAL, QUEBEC, CANADA.

MIXING CHAMBER FOR FLUID-FUEL BURNERS.

Application filed September 21, 1922. Serial No. 589,613.

To all whom it may concern:

Be it known that I, GEORGES A. DE GUIRE, a subject of the King of Great Britain, residing at Montreal, Province of Quebec, 5 Dominion of Canada, have invented certain new and useful Improvements in Mixing Chambers for Fluid-Fuel Burners, of which the following is a specification.

The present invention relates to fluid fuel 10 burners in combination with means for thoroughly mixing the fuel on its way from the inlet or feed supply to the burner.

Among the main objections to burners of this general class are: incomplete mixing of 15 the fuels, complexity of construction, cost of manufacture, liability of the parts to get out of order and lack of compactness. It is the aim of the present invention to overcome these and other objections and provide 20 a simple, compact, inexpensive burner in which the fuel will be very thoroughly and completely mixed preparatory to passing to the point of ignition.

In order to more clearly disclose the construction, operation and use of the invention, reference should be had to the accompanying drawings forming part of the present application. Throughout the several figures of the drawings like reference characters designate the same parts.

In the drawings:

Fig. 1 is a side elevation of the invention, partly broken away;

Fig. 2 is a section on line 2—2 of Fig. 1, 35 and;

Fig. 3 is a side elevation, reduced, showing one element or half used as the entire mixing chamber, the large end being capped.

One of the most important considerations 40 in burners of this type is that of a complete and uniform mixing of the constituents of the mixed fuel. In the present instance, the construction is designed for use with steam and oil, as the fuel constituents, though it is 45 to be understood that the invention is in no way to be construed as limited to their use. Air and oil, or air and steam and oil, or a number of other combinations of fuel ingredients may be equally well used of course.

In the present instance, fuel oil enters the 50 receiving chamber 1 through a suitable connection 2, while steam enters through a connection 3. Preferably, receiving chamber 1 is provided with a suitable base 4 by which 55 it may be bolted or similarly secured to the bases 5. From each base 5 extends a contin-

uous mixing and expansion chamber element consisting of a wall 6 of continuously increasing width concentrically wound upon itself so that each successive coil is spaced 60 at the same distance from the preceding and succeeding coil, throughout its length. The outer end of each of these concentric spiral chambers or coils is closed by a wall 7.

Each of the two expansion mixing chamber elements is complementary to the other and each is provided with a bolting flange 8, by which they may be clamped together by suitable clamping means of any well-known kind—bolts and nuts, for instance, 70 as here shown. When the two are assembled as in Fig. 1, the mixing or expansion chamber is complete and consists of a single continuous chamber or compartment wound upon itself in such manner as to present successive concentric coils of the same radial depth but of steadily and uniformly increasing length from the point of connection of the two elements spirally outwardly 75 toward the respective end of the chamber. 80

The coil of the chamber is directed inwardly, that is, it begins with the outside coil or coil of greatest diameter and least width and passes successively to the coil of least diameter and greatest width. This 85 last and innermost coil terminates in an opening or delivery passage 9 extending longitudinally in one side of the burner pipe 10 which, preferably, is integral with the mixing and expansion chamber. Preferably, the innermost coil constitutes the 90 burner pipe. Suitable burners are threaded into or onto the opposite ends of pipe or innermost coil 10, or either end may be capped, as desired. 95

The fuel constituents entering through 2 and 3 will get a preliminary mixing in 1 from whence the mixture will pass into the first coil and thence through successive coils to the outlet 9 and thence to the burners. 100 As it flows spirally, through the successive coils it expands to fill the increasing volume of the coils. This expansion is in all directions, of course, and, coupled with the oppositely directed spiral paths through 105 which it is compelled to travel insure a very thorough mixing of the constituents of the fuel. To further insure such complete mixing, the outlet opening 9, is made of the same area as the area of the inlet opening or first 110 coil at the point where it receives the fuel mixture from chamber 1. Consequently, the

gas mixture can not pass more quickly through the opening 9 than it passes from the chamber 1 into the end of the first coil. Therefore, the pressure will be maintained throughout the mixing and expansion chamber and the burners will receive their fuel mixture at a steadily uniform or regular pressure which will not be less than that of the pressure of the mixture as it enters the first coil.

As will be readily seen, the mixing chamber may be inexpensively made by two simple castings and easily bolted together. And the receiving chamber is another simple casting quickly bolted to the bases of the elements of the mixing chamber.

The expansion or mixing chamber, as a whole, has been shown as divided laterally. Obviously, it might be divided longitudinally. Likewise, it has been shown as cut into two parts. Clearly, it might be cut into more than two parts. The coils in the construction illustrated, have been shown as of uniform radial depth throughout. That is not necessary. The depth might gradually increase. In that case, the spiral construction could be changed to cylindrical, no coil extending beyond any other. The innermost coil, radially forms the pipe which has its ends extended beyond the other coils and threaded to receive burners. Obviously, therefore, the ends need not be extended but, instead, might be threaded interiorly and the ends of the threaded burners screwed into them.

A modification, to a slight extent, is shown in Fig. 2. In this figure, the mixing chamber is shown as comprising one half of the construction shown in Fig. 1, as though Fig. 1 were cut laterally across between the two flanges 8, the left hand half removed, and a plane disc or cap plate 100 substituted. Of course, the supply pipe connection would then be slightly shifted toward the right so that it would deliver into the chamber. This figure illustrates the use of the single element as a mixing chamber and, therefore, only a conventional fuel connection is shown. Obviously, the connection of Figs. 1 and 2 may be equally well used.

These and many other changes in the construction, arrangement and disposition of the several parts of the invention, within the scope of the claims may be made without in the least departing from the field and scope of the invention and it is meant to include all such within this application wherein only preferred forms have been disclosed by way of illustration.

Having thus described my invention, what I claim and desire to protect by Letters Patent is:

1. A gas mixing chamber comprising an element coiled concentrically upon itself to produce concentric chambers each a con-

tinuation of the preceding one and each of greater length than the one of which it is a continuation, means for delivering fluid fuel to the outer coil, and means for delivering it from the inner one.

2. A gas mixing chamber comprising an element coiled concentrically upon itself to produce concentric chambers each a continuation of the preceding one and each of greater length than the one of which it is a continuation, a spirally disposed wall closing the outer ends of all of said chambers, means for delivering fluid fuel to the outer coil, and means for delivering it from the inner coil.

3. A gas mixing chamber comprising an element coiled concentrically upon itself to produce concentric chambers each a continuation of the preceding one and each of regularly spirally increasing length relatively to the one of which it is a continuation, means for delivering fluid fuel to the outer coil, and means for delivering it from the inner coil.

4. A gas mixing chamber comprising two elements each coiled upon itself to produce concentric chambers of the same radial depth throughout and each a continuation of the preceding one, means for connecting said elements so that the coils of each element become continuations of the coils of the other, means for delivering fluid fuel to the combined outer coils, and means for delivering fluid fuel from the combined inner coils.

5. A gas mixing chamber comprising two elements each coiled concentrically upon itself to produce concentric chambers, each chamber being in continuation of the preceding one, means for connecting said elements so that the coils of each element become continuations of the coils of the other, means for delivering fluid fuel to the combined outer coils, and means for delivering fluid fuel from the combined inner coils.

6. A gas mixing chamber comprising two elements each coiled concentrically and spirally upon itself to produce concentric chambers of the same radial depth throughout and each a continuation of the preceding one, those of one element being extended in an opposite direction longitudinally relatively to those of the other, means for connecting said elements so that the coils of one become continuations of the coils of the other, means for delivering fluid fuel to the outer coils of said chambers and means for delivering fluid fuel from the innermost coils thereof.

7. A gas mixing chamber comprising two elements each coiled concentrically and spirally upon itself to produce concentric chambers each a continuation of the preceding one and each regularly spirally increasing in length relatively to the one of which it is a continuation, the chambers of one element being extended in an opposite

direction longitudinally relatively to those of the other element, means for connecting said elements so that the coils of one become continuations of the coils of the other,

5 means for delivering fluid fuel to the outer coils of said chambers, and means for delivering fluid fuel from the inner coils thereof.

8. A gas mixing chamber comprising an 10 element coiled concentrically upon itself to produce concentric chambers each a continuation of the preceding one and each of regularly spirally increasing length relatively 15 to the one of which it is a continuation, a spirally disposed wall closing the outer ends of all said chambers, means for closing the

opposite ends of said chambers, means for delivering fluid fuel to the outer coil, and means for delivering it from the inner coil.

9. A gas mixing chamber comprising an element coiled concentrically upon itself to produce concentric chambers each a continuation of the preceding one and each of greater length both radially and axially 20 than the one of which it is a continuation, means for delivering fluid fuel to the outer coil, and means for delivering it from the inner one.

Signed at Montreal, Quebec, Canada, this 14th day of September, 1922.

GEORGES A. DE GUIRE.
